UNITED STATES PATENT OFFICE.

THOMAS STEELE, OF COLUMBUS, OHIO, ASSIGNOR TO THE COLUMBUS DENTAL MANUFACTURING COMPANY, OF COLUMBUS, OHIO, A CORPORATION OF OHIO.

INTERCHANGEABLE TOOTH.

1,082,366.

Specification of Letters Patent. Patented Dec. 23, 1913.

Application filed November 25, 1912. Serial No. 733,302.

To all whom it may concern:

Be it known that I, THOMAS STEELE, a citizen of the United States, residing at Columbus, in the county of Franklin and State of Ohio, have invented certain new and useful Improvements in Interchangeable Teeth, of which the following is a specification:

This invention relates to certain new and useful improvements in the method employed in producing interchangeable teeth and attaching the same.

One of the prime objects of my invention is the provision of an artificial tooth constructed to a strict interchangeable standard, which can be readily attached to or removed from the bridge without the requirement of special skill, and, if desired, without the necessity of removing the bridge from the mouth of the patient, and in which, in cases of replacement or exchange of facings, the new facings when attached to the bridge will have their incisal edges, in all cases, conforming exactly to the incisal alinement of the teeth replaced regardless of the length of the teeth, which can be varied to adapt them to the spaces provided for their reception and to compensate for the space which may intervene between the gingival end of the tooth and the gum.

My invention directly and efficiently remedies defects in the art, by the provision of facing elements which may vary as to general form and conformation, but which are each provided with a gaging surface invariably equidistant from the incisal edge of the facing. The immediate result of this settled dimension occurring in each removable facing, is the assurance that the incisal edge of the facing will invariably assume the same relation to the trimmed edge of the backing had by the facing originally applied. Therefore, as the gum recedes, the facings may be successfully removed and replaced by other facings and of larger general dimensions. The second facing applied may extend into closer contact with the gum at the gingival end, but the settled dimension between the gaging surface and the incisal edge of the facing will cause the said incisal edge to register with the trimmed edge of the backing. Therefore, regardless of the length of the tooth facings, the substituted facing will inevitably aline with the trimmed edge of the backing at its incisal edge. This,

as will readily be understood, is particularly 55 advantageous in the application of artificial tooth structure after extraction. During the period of absorption and the consequent recession of the gums, the facings may be successfully removed and replaced by suitable 60 longer facings and yet each substituted facing will aline properly with the trimmed edge of the backing.

Illustrations of my invention are shown in the accompanying drawings, in which 65 similar characters of reference designate corresponding parts, and in which:

Figures 1, 2 and 3 are vertical sections taken centrally of tooth facings successively varying in height, but which all have post 70 sockets whose bases are equidistant from the incisal edges of the facings; Fig. 4 is a projected view showing a rear elevation of the tooth facing element shown in Fig. 3, which elevation is identical in all of these preferred 75 forms of packing; and Fig. 5 is a transverse section of the facing element.

In the drawings, 1 represents the body of a tooth in the rear ground surface of which I form a longitudinal bore 2 extending from the gingival end of the tooth to a point at a predetermined distance from the incisal edge of the tooth, this distance being uniform in all teeth. This bore is accurately centered in the tooth back with relation to the sides thereof and said bore is in all cases parallel with and at a uniform distance from the rear face 3 of the tooth front.

4 is a slot connecting the bore 2 with the rear face 3, said slot being central throughout its length with reference to the bore and extending from the gingival end of the tooth to a point a short distance above the lower end of said bore, thus resulting in the formation of a shallow pocket or socket 5 at the 95 end of the bore.

It will be understood that my improved tooth will slide readily into position in connection with the bridge no matter when, where or by whom the bridge was made. It 100 may be that the dentist may find it necessary or desirable to grind the gingival end or neck of the tooth to make it conform to the patient's gum, but that is all he is called upon to do.

Although I have shown in Figs. 1, 2 and 3 of the drawings, three teeth of different lengths, it will be observed that in each of

said teeth, the distance between the base of the socket 5 and the incisal edge of the tooth, is identically the same.

Because of the fact that all teeth made by my method have exactly the same distance from the incisal edge to the lower end of the slot and bore irrespective of the length thereof, it is possible to make up a bridge even before the teeth in the jaw have been extracted and adapt the tooth fronts on the bridge to fit the gums, at the time the bridge is inserted, then when the gums have receded, as they do in all cases of extraction, the bridge can be left in the mouth and the porcelain tooth front broken off and a new front selected of the same color, character and expression, and of the same width, but longer, and it will slide to position on the old bridge, going to a higher position on the gums, closing up the space that nature has opened, and the incisal edge of the new porcelain tooth front will register along the same line with the gold backing as did the original tooth front. This illustration emphasizes the importance of a standard stop

represented by the lower end of the bore and its definite predetermined distance from the incisal edge.

What I claim, is:

1. The herein described method of forming interchangeable tooth facings which consists in providing each facing with an alining gage for the securing device invariably equidistant from the incisal edge irrespective of the length over all of each facing.

2. The herein described method of forming interchangeable tooth fronts having a bore and slot, which consists in forming the bottom of the bore and slot, respectively, in each tooth front the same distance from the incisal edge, irrespective of the length over all of each tooth front.

In testimony whereof I affix my signature in presence of two witnesses.

THOMAS STEELE.
